SWIMMING PRACTICE APPARATUS

Erhard Hess, Dorchester, Mass.

Application February 10, 1933, Serial No. 656,109

5 Claims. (Cl. 272—71)

This invention relates to machines for instruction in the practice of swimming, being intended more particularly, though not exclusively, for instruction in what is known as the "crawl" (or sometimes the "American crawl") stroke in which the hands of the swimmer pass each through a substantially vertical orbit at the side of the body. In this movement the hands are extended forward in alternation, sweeping downwardly and backwardly, the feet being kicked up or down in alternation and coordinately with the movement of the hands and arms.

In this machine provision is preferably made so that not only are the movements of the hands and feet guided and coordinated to conform to the correct execution of the stroke so that the swimmer learns by practice instinctively to perform such movements, but the mechanism is operated by the muscular power of the swimmer himself so as to develop and train the muscles which primarily come into play in executing this stroke.

The invention will be best understood by reference to the following description when taken in connection with the accompanying illustration of one specific embodiment thereof, while its scope will be more particularly pointed out in the appended claims.

In the drawings:—

Fig. 1 is a side elevation of a machine embodying one form of the invention;

Fig. 2 is a plan view of the machine shown in Fig. 1;

Fig. 3 is a plan of the driving connections between one of the hand straps and the driven sprocket on a somewhat enlarged scale;

Fig. 4 is a cross-sectional elevation on the line 4—4 in Fig. 3;

Fig. 5 is a rear elevation of the machine shown in Figs. 1 and 2;

Fig. 6 is a side elevation of one form of load imposing device associated with the intermediate driven sprocket wheel; and

Fig. 7 is a partial end elevation of the parts shown in Fig. 6 on an enlarged scale and looking in the direction of the arrow in Fig. 6.

Referring to the drawings and to the embodiment of the invention there shown for the purpose of illustration, the apparatus is mounted upon a light but strong portable frame, preferably consisting of angle irons, and comprising primarily a pair of spaced, upright members 11 and 13 connected at their bottom ends by the member 15 and somewhat below their upper ends by the horizontal member 17 forming one side (herein the left-hand side) of the frame. Asso-

ciated with this are corresponding upright members 19 and 21, with a similar lower connecting member and an upper connecting member 23, forming the opposite or right-hand side of the frame, leaving an intervening space in which the subject, hereinafter referred to as the swimmer, is positioned.

The bottom connecting members are prolonged at their rear to provide, in conjunction with uprights 25 and 27 and cross-connecting members 10 29, 31 and 33, a smaller extension of the frame for supporting certain of the operating parts at the rear thereof. At the front the opposite sides of the frame are connected at the bottom by the cross-connecting member 35.

Fixedly secured to upright frame members 36 and between the two sides of the frame is a body rest or table 37 adapted to support the body of the swimmer and on which he lies prone and face downward, his legs extending rearwardly over 20 the two separate leg boards 39, the latter being hinged to the rear edge of the body rest or table 37 so as to be freely movable up and down with relation thereto and provided each at its rear end with a foot rest or holder 41 adapted to receive the toes of the swimmer and hold the feet and legs in fixed position on the leg boards, so that movements imparted to the latter are adapted to direct the movements of the swimmer's legs. Each foot holder 41 is fastened by a bolt 30 extending through the slot 43 in the leg board so as to be adjustable for persons of different leg lengths.

Each leg board has journaled on its under side a cam roll 45 riding on its own cam 47, the two 35 cams being secured to a common cam shaft 49 journaled in bearings supported by the rearwardly extending and upwardly inclined frame members 51. The two cams 47 are set 180° apart and are preferably designed to provide a uniform 40 rising and falling movement for the leg boards.

To guide the swimmer's hands and arms in the proper orbit there is provided at each side of the frame and rigidly secured thereto a closed, guiding trackway 53 of the shape best shown in Fig. 1, 45 where it will be seen that it comprises an upper, substantially horizontal portion merging into a lower portion which conforms to the arc of a circle. The trackways thus present guides which define in each case a non-circular orbit lying in a substantially vertical plane at each side of the swimmer. This trackway herein consists of a continuous, relatively thin strip of metal but of generally rectangular cross-section, there being 50 55

two similar guiding trackways, one for the right arm and another for the left arm.

Mounted to run easily and with slight friction on the trackway is a small, light guide frame 5 comprising the grooved rollers 55, 55 (Fig. 3) engaging the opposite convex edges of the trackway strip, the rollers being journaled in the plate 51 which holds them in fixed relation to the trackway but is pivotally secured to the sliding connecting rod 59 through which the machine is driven by the movement of the swimmer's arms. The arm propelling mechanism for the two opposite sides of the machine is substantially the same and one only need be described.

15 Means are provided to permit the swimmer to grasp and simultaneously move the two connecting rods 59, and for this purpose there is attached to each rod a holding strap 61 adapted to encircle and be fastened about the palm of the hand, allowing the hands to remain open in executing the arm stroke. Each strap has a swivel attachment to its connecting rod by means of a bolt secured in a threaded hole in the connecting rod, a spaced series of holes being provided so that 20 the position of the strap may be adjusted to suit the reach of the individual.

The forward and downward movement of the swimmer's hand acts through the connecting rod 59 to rotate a shaft 63 journaled in bearings on 25 the frame member 17 (the right-hand shaft being journaled on the frame member 23), the axis of this shaft being aligned in close approximation to the shoulder of the swimmer about which the sweep or full movement of the arm takes place 30 and coinciding substantially with the center of the arc to which the lower run of the guiding trackway conforms.

On the shaft 63 is mounted a sprocket wheel 65 driven through a compensating mechanism, later 40 described, and acting in turn to impart the necessary movement to the foot board cam 47. Since the radial distance between the shaft 63 and the trackway 53 varies at different points in the orbital movement of the hand, the connecting rod 45 59 is mounted for sliding movement in the two opposite arms of the crank member 67 (Fig. 3), which latter is fixedly secured to the shaft 63. The result is that as the hand sweeps forward 50 along the upper horizontal run of the trackway toward the downwardly extending part thereof, the connecting rod slides outwardly in its crank arm increasing the effective radius or leverage, and as it moves back on the horizontal run of the trackway it slides into the crank arm decreasing 55 its effective radius or leverage.

The two opposite sprocket wheels 65 are connected each by a sprocket chain to drive sprocket wheels 68 fixed on opposite ends of the intermediate shaft 69, the latter journaled in bearings 60 secured on the upright frame members 25 and 27, the shaft 69 in turn having fixedly secured to it the larger intermediate sprocket wheel 71 connected by a sprocket chain to drive the smaller, rear sprocket wheel 73 secured to the foot-board 65 cam shaft 49 for turning the foot-rest cams 47.

The two roller guide frames occupy positions at all times 180° apart with relation to the axis of the shaft 63. The sprocket wheels 65 and 68 are of the same size so that the shaft 69 and sprocket wheel 71 make one complete revolution 70 for each complete cycle of arm movement. The intermediate sprocket wheel 71 is herein three times the diameter of the sprocket wheel 73, so that for each complete cycle of arm movement the 75 cams 47 each complete three revolutions, enforc-

ing three beats or complete reciprocations of each leg board or an aggregate of six beats for the two legs of the swimmer, the movements of the two legs being opposite to each other and in alternation. This provides the leg movement ordinarily used in the American crawl stroke, but by replacing the intermediate sprocket wheel 71 or the cam shaft sprocket wheel 73 with wheels of different sizes, the number of beats for each cycle of arm movement may be varied as desired.

During the forward movement of one guiding frame, for example, the left-hand frame, on the horizontal run of trackway, and until it reaches the arc-shaped portion thereof, the other or right-hand guiding frame is traveling on the arc-shaped portion and at a relatively greater linear velocity than the first or left-hand frame. Accordingly, the movement of the right-hand shaft 63 driven thereby tends to accelerate with relation to the movement of the companion or left-hand driving shaft. To prevent the acceleration in the movement of one shaft from interfering with the simultaneous retardation of the movement of the other shaft, a lost motion or compensating driving connection (Figs. 3 and 4) is provided between each 15 shaft and its driven sprocket wheel 65, both of which, it will be recalled, are chain-gearred to the same intermediate driving shaft 69.

For this purpose the sprocket wheel 65 is loose on the shaft 63 but is provided with a pin 75 positioned eccentrically and extending laterally from the inside face of its hub. The pin 75 projects into a recess 77 formed in the opposing face of a collar 79 fixedly secured to the shaft 63. When the shaft 63 is rotated the collar and pin serve 30 as the driving connection for the sprocket wheel. The recess 77, however, permits the pin to move therein and the shaft 63 on one side of the machine to lag behind its sprocket wheel when the shaft on the opposite side is accelerated by the 40 travel of its guiding frame over the arc-shaped portion of the trackway.

This not only relieves any binding action in the gearing connection between the two shafts 63, but automatically transfers the load of driving 45 the apparatus to the arm which is executing the downward, backward and upward sweep, presenting an increased resistance thereto, while relieving from any substantial load the other arm which is being extended forwardly. This simulates the conditions in actual swimming, where the downward and backward sweep of the arm is the movement through which propulsive power is imparted to the stroke against the resistance of the water, while the subsequent forward movement of the arm is merely intended to reposition the hand for repeating the power stroke.

If desired, means may be provided additionally to impose an artificial load on the arm movement when executing the first part of the downward and backward sweep where somewhat more resistance is encountered in performing the stroke in the water than in the finishing part of the sweep. As illustrative of such means (see Figs. 6 and 7) there is shown as secured to one 50 face of the intermediate sprocket wheel 71 two oppositely positioned and spaced segmental brake shoes 81, in the path of the periphery of which there lies a curved spring 83 adapted to exert a frictional drag on the sprocket wheel when the 55 shoe passes thereover. The free end of the spring rests slidably in a yoke 85 supported between the frame members 51. The result is that as one arm of the swimmer sweeps down over the first part of the arc-shaped portion of the trackway, one 75

of the shoes engages with and passes over the spring, adding somewhat to the resistance encountered by the movement of the arm, this additional resistance being relieved during the time 5 the arm performs its upward sweeping movement, but a similar and similarly timed resistance being imposed on the other arm when the other segmental shoe passes over the spring 83. It will be observed that the radial distance from the 10 center of the sprocket wheel to the periphery of each brake shoe is greater near the middle of the shoe and decreases somewhat toward each end, the result being that the effort required to be exerted by the swimmer in the execution of the 15 power stroke first increases and then decreases in close simulation to the effort called for in executing the stroke in the water.

The operation of the apparatus will be readily understood from the foregoing. To operate the 20 machine, the swimmer lies face downward on the table, placing each foot in the respective foot rest and placing each hand in the hand strap provided. Adjustment may be made in each case to accommodate the stature of the swimmer. 25 By pushing the roller guiding frames forward and around the trackway the driving mechanism is set into operation, causing the legs to move up and down in the desired ratio and in coordination with the movement of the arms.

30 This not only provides a beneficial exercise and a means for teaching the novice the correct stroke, with perfect coordination of the movement of the legs and arms, but also a means for perfecting the stroke and keeping in practice 35 where swimming facilities are not available, and at the same time develops the muscular power required for performing the stroke.

While I have herein disclosed and described for the purpose of illustration one specific embodiment of the invention, it is to be understood that 40 this is illustrative only and that extensive deviations and changes may be made in the apparatus herein illustrated, all within the scope of the claims and without departing from the spirit 45 of the invention.

I claim:

1. In an apparatus for instructing in the crawl 50 stroke of swimming, the combination with means for supporting the body of the swimmer in prone position, of means for directing the movement

of the two hands alternately first forward and then downward and backward in a substantially vertical plane, and mechanism driven by the movement of said hands, said mechanism having means to present a greater resistance to the downward movement of each hand than to the forward movement thereof. 5

2. In an apparatus for swimming instruction, the combination with means for supporting the body of the swimmer in prone position, connections for attaching to the apparatus the legs and arms of the swimmer, mechanism for guiding and coordinating the movements of the arms and legs, means for driving said mechanism through the muscular power of the swimmer, and means for 10 imposing a different load on the swimmer for different parts of the swimming stroke. 15

3. In an apparatus for swimming instruction, the combination with means for supporting the body of the swimmer in prone position, of a non- 20 circular guiding trackway defining an orbit for each hand of the swimmer, means adapted to be secured to each hand of the swimmer for guiding said hand along said trackway, a driving member connected to be rotated by the movement of each 25 hand through said orbit, a driven member for each driving member, said driven member being interconnected to maintain the hands in fixed relationship one to the other, and a lost motion connection between each driving and driven 30 member.

4. In an apparatus for swimming instruction, the combination with means for supporting the body in prone position, of a non-circular guide for directing the movements of each hand of the 35 swimmer in an orbital path in alternation first forwardly and then downwardly and backwardly, a driving member connected to be driven by the movement of each hand at a varying rate of speed in different parts of the orbital path, a driven 40 member, and a lost motion connection between the driving and driven member.

5. In an apparatus for swimming instruction, the combination with means for supporting the body of the swimmer in prone position, of a guide 45 for each hand defining a non-circular orbit, mechanism driven by the joint movement of said hands, and a lost motion driving connection between each hand and the said driving mechanism.

ERHARD HESS 50
